METHOD OF MAKING ENVELOPES WITHOUT
SIDE FLAPSGunnar Holmlund, Goteborg, Sweden, assignor to
Maria (Majen) Lindgren, Goteborg, SwedenApplication September 9, 1939, Serial No. 294,186
In Sweden December 15, 1937

4 Claims. (Cl. 93—35)

It is known to manufacture envelopes from paper blanks having a rectangular centre panel, to form the front side of the envelope, and flaps projecting from the four edges of that rectangular panel, the bottom flap and the two side flaps being folded over and stuck together with gum arabic, to form the back of the envelope. The fourth flap, which constitutes the closure flap of the envelope, is coated either with gum arabic or with rubber solution; in the latter case a similar coating of rubber solution must be applied to the back of the envelope in such a way that the two rubber coatings come together (one on top of the other) when the envelope is closed. A rubber coating of the kind referred to has the property of adhering to a similar coating of rubber when both coatings are dry, that is to say, when the solvent has evaporated from the rubber solution. On the other hand, these rubber coatings will not adhere to surfaces which are not rubber coated. Gum arabic does not adhere to any other object when in a dry condition but sticks to other objects when moistened.

It is also known to make envelopes without side flaps by gluing a bottom or back flap to the front panel, with gum arabic, applied along the side edges.

According to the process which forms the subject matter of the present invention, a paper band fed from a roll of paper, which has a transverse width sufficient for two envelopes side by side, is provided on one surface with a longitudinal stripe or stripes of rubber solution, where the closure flaps are to be located, and, on the other side of the paper, with other longitudinal stripes of rubber solution, at those places which register with the closure flap stripes when the envelopes are closed, that similar coatings of rubber solution are applied, on the first mentioned side of the paper, along lines which run transversely to the length of the band and which correspond to the side edges of the envelopes that the applied stripes of rubber solution are dried, that the two side edges of the paper band are then folded along the lines which are to form the bottom edges of the envelopes, that the paper band is next divided longitudinally along its middle line and that, finally, the envelopes are cut apart transversely along their hitherto connected side edges.

A machine for carrying out the method of the invention is illustrated diagrammatically in the accompanying drawing, in which:

Figure 1 shows the machine in plan view (as seen from above) with some parts omitted, while

Figure 2 shows the same machine in side elevation.

Figure 3 shows the back of an envelope as produced on this machine.

A continuous web or band of paper 1, the width 5 of which corresponds to the width of two unfolded envelope blanks is drawn off from a roll of paper 2 and brought under scoring wheels 3, which produce folding lines or creases, as at 4, corresponding to the bottom edge 5 of the folded 10 envelopes and further creases 6 for the folding of the top closure flap 8. The paper then passes under stamp rolls 9 which are so constructed and operated that they apply rubber solution in regularly spaced stripes 10 running transversely 15 across the band 1. In a later stage the envelopes are cut apart along the medial lines of the stripes 10. Thus the side edges 11 of the envelopes (Fig. 3) correspond to the lines of severance and immediately adjacent these side edges 11 there remain adhesive rubber coatings, half the width 20 of the stripes 10.

After leaving the rolls 9 the paper band passes under a roll 12, which applies a longitudinal stripe 13 of rubber solution. This stripe 13 is subsequently parted longitudinally into two stripes which form the adhesive coatings of the closure flaps of the envelopes, as seen in Fig. 3. Next the paper band passes over rolls 14 (Fig. 2), which apply stripes 15 of rubber solution to the other side of the paper, near to the longitudinal edges of the band, as indicated in Fig. 1. Fig. 3 shows the position of the stripe 15 in the finished envelope.

When the stripes of rubber solution have been applied at the requisite places on the moving band 1 the coatings must be dried. For this purpose the coated paper band may be directed upwards, as at 16, for drying in the open air or 30 in an apparatus (not shown) designed to facilitate the drying operation.

When the coatings have dried the paper band is brought down again, at 17, and thence to a flap folding device 18, which folds over both edges 45 of the paper along the score lines or creases 4. In this operation the stripes 10 are, at the same time, folded upon themselves and thereby the side edges 11 of the front panels and the back flaps of the envelopes are brought into adherent 50 contact with each other. Firm adhesion may be ensured by a further pressing together of the envelopes thus folded. This can be accomplished by a pair of rollers 19. At suitable points holes 20 are punched, by a stamp 21, at the ends of 55

the flaps 8, so that notches 22 are formed in the finished envelopes. These notches facilitate the insertion of a paper knife, when opening an envelope that has been sealed up. The paper band then passes under a cutting wheel 23, which cuts the paper along the longitudinal middle line, thereby separating the rows of envelopes at the edges of their closure flaps. Finally the two paper webs resulting from the longitudinal cutting of the band 1 are severed transversely by a knife 24, which thus cuts off two envelopes at a time, and the finished envelopes 26 fall into a tray 25.

The rolls 19, already referred to, exert a feeding action on the paper band 1 but this can be supplemented by the provision of additional feed rolls, for instance the rolls 27, receiving the downward run 17 of the band may be operated as feed rolls. As supports for the band 1 and as counter rolls for the scoring wheels 3 and the adhesive applying rolls 9 and 12, supporting rolls such as 28 may be used in any requisite number. Counter rolls 29 are arranged above the adhesive applying rolls 14. The adhesive rubber stripes 10, 13 and 15 may each comprise several lines of adhesive instead of one line only. The scoring wheels 3 may be dispensed with as also may the stamps 21. Adjacent the places where the rubber solution is to be applied cups or troughs 30, each containing a stock of solution are arranged and dipper rolls 31 raise the solution from these troughs in order that it may be transferred to the adhesive applying rolls.

The method described cannot be used with gum arabic, because inside the folding apparatus 18 there must be inserted, in known manner, a stationary metal band or the like to hold the paper down on to the inner angle of the apparatus 18, and a gum arabic solution could not be made to pass such metal band without being scraped off by the metal band which would smear it over the inside of the envelope, the whole interior of which would therefore get stuck together.

45 In place of the vertically reciprocating stamps 21, rotating stamps may be used and may, if desired be located close to the adhesive applying roll 9. The holes 20 may serve for controlling the feed of the paper or the operation of the 50 knife 24, so that the line of severance of the envelopes falls exactly in the middle of the holes 20. The rotating stamp may, for instance, be arranged on the same shaft as and between the rollers 9.

55 I claim:

1. The method of making envelopes without side flaps out of a continuous web or band of paper, which is coated with adhesive substance, cut and folded, consisting in providing a paper band fed from a roll of paper, which has a transverse width sufficient for two envelopes side by side, on one surface with a longitudinal stripe or stripes of rubber solution, where the closure flaps are to be located, and, on the other surface of the 60 paper with other longitudinal stripes of rubber solution, at those places which will register with the closure flap stripes when the envelopes are closed, applying similar coatings of rubber solution on the first mentioned side of the paper 65 along lines, which run transversely to the length of the band and which correspond to the side edges of the envelopes, drying the applied stripes of rubber solution, then folding the two side edges of the paper band along the lines which are to form the bottom edges of the envelopes, di-

viding the paper band longitudinally along its middle line, and finally cutting envelopes apart transversely along their hitherto connected side edges.

2. The method of making envelopes without side flaps out of a continuous web or band of paper, which is coated with adhesive substance, cut and folded, consisting in providing a paper band fed from a roll of paper, which has a transverse width sufficient for two envelopes side by side, on one surface with a longitudinal stripe or stripes of rubber solution, where the closure flaps are to be located, and, on the other surface of the paper with other longitudinal stripes of rubber solution, at those places which will register with the closure flap stripes when the envelopes are closed applying similar coatings of rubber solution on the first mentioned side of the paper along lines, which run transversely to the length of the band and which correspond to the side edges of the envelopes, drying the applied stripes of rubber solution, then folding the two side edges of the paper band along the lines which are to form the bottom edges of the envelopes, dividing the paper band longitudinally along its middle line, finally cutting the envelopes apart transversely along their hitherto connected side edges, and providing the continuous paper band with longitudinal folding lines or creases corresponding to the bottom edges 20 and the top edges of the envelopes in order to facilitate the folding over of the bottom flap portion and the closure flap portion of the said band.

3. The method of making envelopes without side flaps out of a continuous web or band of paper, which is coated with adhesive substance, cut and folded, consisting in providing a paper band fed from a roll of paper, which has a transverse width sufficient for two envelopes side by side, on one surface with a longitudinal stripe or stripes of rubber solution, where the closure flaps are to be located, and, on the other surface of the paper with other longitudinal stripes of rubber solution, at those places which will register with the closure flap stripes when the envelopes are closed, applying similar coatings of rubber solution on the first mentioned side of the paper along lines, which run transversely to the length of the band and which correspond to the side edges of the envelopes, drying the applied stripes of rubber solution, then folding the two side edges of the paper band along the lines which are to form the bottom edges of the envelopes, dividing the paper band longitudinally along its middle line, finally cutting the envelopes apart 45 transversely along their hitherto connected side edges, and providing the paper, after the drying of the adhesive stripes thereon with perforations, such as punched holes, so located as to produce notches in the side edges of the closure flaps 50 when the envelopes are cut apart.

4. The method of making envelopes without side flaps out of a continuous web or band of paper, which is coated with adhesive substance, cut and folded, consisting in providing a paper band fed from a roll of paper, which has a transverse width sufficient for two envelopes side by side, on one surface with a longitudinal stripe or stripes of rubber solution, where the closure flaps are to be located, and, on the other surface of the paper with other longitudinal stripes of rubber solution, at those places which will register with the closure flap stripes when the envelopes are closed, applying similar coatings of rubber solution on the first mentioned side of the paper 70

along lines, which run transversely to the length of the band and which correspond to the side edges of the envelopes, drying the applied stripes of rubber solution, then folding the two side edges 5 of the paper band along the lines which are to form the bottom edges of the envelopes, dividing the paper band longitudinally along its middle line, finally cutting the envelopes apart transversely along their hitherto connected side edges, 10 and providing the continuous paper band with longitudinal folding lines or creases correspond-

ing to the bottom edges and the top edges of the envelopes in order to facilitate the folding over of the bottom flap portion and the closure flap portion of the said band and providing the paper, after the drying of the adhesive stripes 5 thereon with perforations, such as punched holes, so located as to produce notches in the side edges of the closure flaps when the envelopes are cut apart.

GUNNAR HOLMLUND. 10
